UNITED STATES PATENT OFFICE

WILLIAM H. KITTO, OF CANTON, OHIO, ASSIGNOR TO THE HOOVER COMPANY, OF NORTH CANTON, OHIO, A CORPORATION OF OHIO

SUCTION CLEANER

Application filed May 28, 1930. Serial No. 456,386.

The present invention relates to suction cleaners and more particularly to a new and novel suction cleaner construction in which, through the use of agitation and directed air flow, increased cleaning efficiency is made possible. The invention is of simple construction and performs, in the cleaning operation, the desirable functions usually found only in more complicated machines.

10 The object of the present invention is the provision of a new and improved suction cleaner. A further object is the provision of a suction cleaner which is simple in its construction and which combines the desirable qualities of durability, economy, and efficiency. A further object is the provision of a new and improved agitator for suction cleaners. A further object is the provision of a suction cleaner agitator which 20 controls the direction of air flow in the suction cleaner nozzle by its position therein which is determined by the direction of movement of the suction cleaner. Other and more specific objects will appear upon reading the following specification and taking into consideration the drawing annexed.

Referring to the drawing:—

Fig. 1 is a side view of a suction cleaner constructed in accordance with the present invention showing the suction nozzle and agitator therein in cross section;

Fig. 2 is a partial cross section upon the line 2—2 of Fig. 1.

Referring now to Fig. 1 in particular, a suction cleaner indicated by the reference character 1 is shown which comprises a suction nozzle 2; a fan chamber 3 which houses a fan not shown; a motor casing 4 which encloses the fan-propelling motor; front-supporting wheels 5, of which one is shown, and rear supporting wheels 6; and a handle bail 7 adapted to be connected to a handle in order that the cleaner may be propelled over the surface covering when in use. The aforementioned parts are found in the usual suction

cleaner and no invention resides in their general arrangement as shown.

Suction nozzle 2 is formed with front and rear walls 8 and 9 respectively, which extend substantially parallel throughout their length. Nozzle lips 10 and 11 which are positioned at the lower edges of nozzle walls 8 and 9 are of the type known as sealing lips, they being of considerably greater breadth than the usual nozzle lips and functioning, in the operation of the machine, to restrict the air flow between themselves and the surface covering undergoing cleaning in the nozzle. The ends of nozzle 2 are closed by removable end plates 12, of which one is shown in Fig. 2, which are removably secured in place by securing means 13.

Positioned within nozzle 2 and extending the length thereof is the agitating tunnel member, indicated by the reference character 14. Tunnel 14 comprises a hollow body member with converging side walls 15 and 16 of relatively narrow width along their surface-contacting edges or lips 15A and 16A, said lips being of such magnitude that they are adapted to penetrate between adjacent rows of pile of a surface covering and function as surface-agitating means in the operation of the cleaner. Each end wall 17 of tunnel 14 is provided with a cylindrical perpendicular extruded wall 18 which is rotatably mounted within a bushing 19 which is firmly held in the opening 20 of the adjacent plate 12. The same pressure exists at all times within tunnel 14 as exists outside the nozzle 2, as the interior of tunnel 14 is directly connected to the exterior atmosphere through the passageways formed by walls 18. Positioned upon the upper surface and extending the length of member 14 are sealing stops 21 and 22 which are so positioned that the rotation of the tunnel in the bushings 19 is limited to a position on either side of its center position, which would be the position in which a longitudinally bisecting plane be-

tween lips 15A and 16A would be vertical, in which one of the walls 15 and 16 of the tunnel is approximately parallel to the nearest adjacent wall 8 or 9 respectively of the nozzle. With the tunnel member at its maximum angular displacement on either side of its center position one of the sealing stops contacts the adjacent wall of the nozzle across its length and effectively prevents the passage of air between the tunnel and the nozzle wall at that side of the tunnel in response to the demand created by the suction fan within the chamber 3.

In the operation of a suction cleaner constructed in accordance with the present invention, the movement of the cleaner over the surface covering results in the tilting of the agitating tunnel 14 in either a rearwardly or forwardly direction as the walls 15 and 16 extend a sufficient distance below the plane of the nozzle lips 10 and 11 to contact the surface covering even though said covering remains flat upon the floor and unaffected by the vacuum within the nozzle 2. As viewed in Fig. 1 the cleaner is moving in a forward direction, that is to the left, and the tunnel 14 has been tilted rearwardly. The operation of the motor-driven fan within the fan chamber 3 draws the air from the suction nozzle 2 and creates a pressure therein which is lower than the atmospheric pressure without. Influenced by the difference in pressure within the nozzle and between lips 15A and 11 the floor covering therebelow is lifted into contact therewith. With the surface covering in the raised position the broad sealing lip 11 substantially prevents the flow of air between itself and the covering because of its large area and the air entering the nozzle in response to the demand created by the difference in pressure enters through the tunnel 14 and passes under the lip 16A of the wall 16, having first entered the tunnel through the openings formed by the cylindrical walls 18 at the ends thereof. Through the action of seal 21 the space within the nozzle 2 between the wall 15 and the wall 8 is sealed from the remainder of the nozzle and the effect of the diminished pressure within said nozzle is not felt in that space. As a result the surface covering below the lip 10 of wall 8 and the wall 15 is unaffected by the reduced pressure within the nozzle and remains in contact with the floor. With the advance of the cleaner in the forward direction, as aforescribed, the wall 15 extends the greatest distance into the plane of the nozzle mouth and, because of the relatively narrow width of its lower edge or lip 15A, penetrates between the individual rows of pile and between the individual tufts of a single row thereby functioning to flex and agitate said pile and dislodge the dirt therefrom and therebetween. The lower edge or lip 16A of the wall 16 of the tunnel 14, while

positioned at a greater height than the corresponding part of wall 15 with the tunnel tilted rearwardly extends into contact with the surface covering which is bowed up between the wall 15 and the lip 11 of the rear wall 9 of the nozzle. The air entering the suction nozzle 2 under the lip of the wall 16 from the tunnel 14 in response to the pressure difference must contact and pass through the pile of the lifted surface covering in order to gain entrance into said nozzle. The edges or lips of both walls 15 and 16 perform the function of vibrating and agitating the pile of the surface covering as they are slid thereover and the cleaning air entering the nozzle from the tunnel 14 between the lips 51A and 16A is directed to the immediate point of surface agitation and maximum cleaning efficiency is encompassed. With the cleaner propelled in the opposite direction the tunnel 14 assumes the position indicated by the dotted lines showing in Fig. 1. The surface covering then becomes bowed up between the lip 16A and the lip 10 while the sealing stop 22 performs the sealing function aforescribed relative to the stop 21 with the machine moving in the forward direction.

The entire construction is simple and the well known additional cleaning efficiency resulting from the inclusion in a cleaner of agitating means is encompassed by the present invention without resort being had to the connection between the agitating means and the driving motor, with the consequent saving in manufacturing costs through greater simplicity. The construction makes use of the principle of positive pile agitation and incorporates therewith the desirable quality of having the cleaning air directed to the point of agitation.

Having clearly set forth and described my invention I claim:

1. In a suction cleaner, a suction nozzle, means to create a reduced pressure in said nozzle, a member rotatably mounted within said suction nozzle interiorly connected to the atmosphere and adapted to be tilted by the movement of the cleaner over the surface covering undergoing cleaning, and means to limit the angle of rotation of the member and to prevent the passage of air between the member and the adjacent wall of the nozzle comprising a sealing stop carried by said member along its entire length and adapted to contact the adjacent wall of said suction nozzle.

2. In a suction cleaner of the type adapted to lift the surface covering undergoing cleaning from the supporting surface, suction-creating means, a nozzle connected to said suction-creating means, broad sealing lips carried by said nozzle defining the sides of the mouth thereof and adapted to contact a surface covering lifted by the suction within said nozzle created by said suction-

creating means, a tiltably mounted hollow member within said nozzle interiorly connected to the atmosphere, spaced pile penetrating lips defining an opening in said member and adapted to contact a surface covering undergoing cleaning, and means to limit the tilting of said member so that at all times at least one of said lips is in a surface-contacting position.

10 Signed at North Canton, in the county of Stark and State of Ohio, this 14th day of May, A. D., 1930.

WILLIAM H. KITTO.
